MEDICAL SEMI-PERMEABLE MEMBRANE SUPPORT

Ferris E. Newman, Libertyville, Ill., assignor to
Baxter Laboratories, Inc., Deerfield, Ill.

Filed Jan. 24, 1975, Ser. No. 543,748

Term of patent 14 years

Int. Cl. D23—01; D24—02
U.S. Cl. D83—1 F

Fig. 1.

Fig. 2.

Fig. 3.

FIG. 1 is a plan view of a length of membrane support, showing my new design;

FIG. 2 is a plan view of the other side of the length of membrane support shown in FIG. 1; and

FIG. 3 is an elevational view of the membrane support of FIGS. 1 and 2.

I claim:

The ornamental design for a medical semi-permeable membrane support, substantially as shown and described.
